DESIGN FOR A SETTEE

Robert M. Ferguson, Dania, Fla.

Application June 3, 1936, Serial No. 62,997

Term of patent 14 years

To all whom it may concern:

Be it known that I, Robert M. Ferguson, a citizen of the United States, residing at Dania, in the county of Broward and State of Florida, have invented a new, original, and ornamental Design for Settees, of which the following is a specification, reference being had to the accompanying drawing, forming part thereof.

I claim:

The ornamental design for a settee, as shown.

ROBERT M. FERGUSON.
